UNITED STATES PATENT OFFICE.

BENHARD YOCH, OF ST. LOUIS, MISSOURI.

TRACTION-ENGINE.

SPECIFICATION forming part of Letters Patent No. 269,496, dated December 19, 1882.

Application filed July 31, 1882. (No model.)

To all whom it may concern:

Be it known that I, BENHARD YOCH, of the city of St. Louis, in the State of Missouri, have invented certain new and useful Improvements in Traction and Portable Engines, of which the following is a specification, reference being had to the accompanying drawings, forming part of the same.

My improvement relates to a portable engine for driving machinery, and which has capacity in itself for moving from place to place and for use as a traction-engine.

The first part of my improvement consists in making the body of the engine adjustable vertically upon the axle of the main wheels, and placing upon the crank-shaft friction-wheels that may be brought in contact with the main supporting-wheels to turn them.

My improvement also consists in the insertion of a cushion between these wheels and the crank-shaft, and driving the wheels by means of a crank-and-link connection with the shaft, so as to allow the compression of the cushion.

My improvement also consists in the described means for adjusting the position of the crank-shaft.

My improvement also consists in combining with the crank-shaft a windlass and cog-gear, by which the engine may be used when at rest to draw forward a wagon or other object, and the described means for throwing the same in and out of gear.

In the drawings, Figure 1 is a side elevation of the engine, with the two near wheels removed and their axles shown in section. The drive-pulley is also removed. Fig. 2 is a perspective view of one of the pulleys of the steering-chain, and Fig. 3 is a similar view of the other chain-pulley. Fig. 4 is an enlarged detail illustrating the arrangement of lever by which the windlass-clutch mechanism is operated. Fig. 5 is a rear elevation of the engine. Fig. 6 is a front elevation of the engine. Fig. 7 is a side elevation of one of the friction-wheels. Fig. 8 is a diametric section at 8 8, Fig. 7. Fig. 9 shows one of the friction-wheels, part in face view and part in section. Figs. 10 and 11 are detail views, showing the ratchet device for raising and lowering the crank-shaft and friction-wheels.

The main ground-wheels are shown at A and the steering-wheels at B.

C is the boiler, which forms the body of the engine.

D is the axle of the wheels A. The axle is vertically adjustable in guide-brackets E', attached to the sides of the boiler. The axle D is secured in the brackets by means of guide-blocks F, through which the axle passes, and which slide in the brackets.

G is a jack-screw which works in the bracket, and whose lower end bears upon the block F, so that when the jack-screw is turned down in the bracket it raises the boiler and all parts that are fastened rigidly to it. The screw is turned by means of a ratchet-lever, H, whose ratchet-pawls I and J engage two sets of ratchet-teeth upon the screw. One pawl, I, and its teeth I' act to cause the downward movement of the screw, and the pawl J and its ratchet-teeth J' act to turn the screw upward. The pawls I and J are upon a single rock-shaft, K, having a toe, L, engaged by a spring, M, which acts to hold whichever of the pawls may be in use against its ratchet-teeth, and at the same time to hold the other pawl out of contact with its proper teeth.

The engine-cylinders and their valve-chests are shown at N.

O are the connecting-rods, engaging cranks on the crank-shaft P. The crank-shaft has bearing in the frame E. Upon the crank-shaft P are friction-wheels R—one over each of the main wheels A. The construction is such that when the wheels R are in their lower position they bear upon the main wheels A, and, when the crank-shaft turns, cause the rotation of the main wheels and the movement of the engine over the ground. The friction-wheels are cushioned upon the shaft by india-rubber bushing R', so as to form a spring between the pulley or wheel R and the shaft, and so between the main wheel and the frame E. The wheel is coupled to the shaft, so as to cause its rotation therewith, by a link, S, connected by pintles at the ends to the wheel, and a crank-arm, S', fixed to the shaft. This connection will allow free movement of the pulley in the compression of the spring-cushion R'.

T are eccentrics upon the crank-shaft by which the slide valves T' are operated.

U is a spur-wheel upon the crank-shaft, that may be made to engage a spur-wheel, V, upon a windlass-drum, W. The drum W turns free,

and has also endwise movement on an arbor, X , fixed to the frame E in a position parallel to the crank-shaft. The drum is for reception of a cable that is coiled thereon, and which 5 extends from the drum, first over a grooved pulley, Y , and then under a grooved pulley, Z , and then to any object it may be desired to draw toward the engine. The pulleys Y and Z turn free on the arbors a , and have endwise 10 movement thereon to accommodate themselves to the position of the cable upon the drum. The drum has capacity for endwise movement upon the arbor X to bring the spur-wheel V into engagement with the spur-wheel U and to 15 allow its disengagement. The endwise movement of the drum upon the arbor X is caused by a hand-lever, b , having a stud, b' , entering a circumferential channel in a wheel, c , that is fixed to one end of the drum.

20 d is the brake, operated by connection to a brake-lever, e .

f is the steam-pipe, and g the exhaust-pipe, the latter extending through a feed-water heater, h , to the chimney i .

25 The fore end of the boiler is supported on the wheels B by means of a "fifth-wheel," j , the axle k turning on the fifth-wheel to guide the machine. The axle is turned by means of two chains, l , fixed at one end, l' , to the bottom of 30 the boiler, and passing through pulley-blocks m near the ends of the axle, and back to a windlass, n , turned by a worm-gear, o , operated by a hand-wheel, p . The ends of the chain are coiled around the windlass in opposite directions, so that as one end is coiled 35 up the other end is uncoiled. It will be seen that the whole weight of the heavy end of the boiler may be brought upon the wheels R when the engine is moved from place to place, and 40 that the rubber cushions will act to prevent jars being communicated from the ground-wheels to the engine. Thus a considerable amount of frictional power may be applied to the ground-wheels without injurious shaking 45 of the working parts.

P' is a belt-pulley by which motion may be

communicated to any machinery through medium of a belt thereon.

I claim as my invention—

1. A portable or road engine having its rear 50 portion vertically adjustable to adapt it to be supported either on the axle of or on the top of the main wheels, as set forth.

2. In a portable or road engine, the frame E , vertically adjustable on the main wheels to 55 support the rear portion of the engine either on the axle of or on the top of the main wheels, as set forth.

3. The combination, with the wheels R and A , and frame E , and axle D , of the jack-screws 60 G , turning in the frame and bearing upon the sliding axle-bearing F , substantially as and for the purpose set forth.

4. The combination, with frame E , main wheels A , and axles D , of the levers H , each 65 having rock-shaft K , provided with pawls I and J , toe L , and spring M , the jack-screw G , and ratchet-collars I' and J' , the said levers adapted to raise and lower the jack-screws by 70 the engagement of the pawls with the ratchet-collars, as set forth.

5. The combination, in a portable or road engine, of the engine crank-shaft, spur-wheel U thereon, arbor X , windlass W , having rotary and endwise movement on the arbor, spur-wheel V on the windlass, arbors or rods a , and pulleys Y Z on the said arbors or rods, substantially as and for the purpose set forth. 75

6. The combination, with the shaft P and the friction-wheel R , of the rubber cushion R' , 80 and crank S' , and link S , substantially as and for the purpose set forth.

7. The combination of a driving or driven shaft, and a wheel or pulley thereon, a cushion interposed between the shaft and wheel, 85 and a driving-connection between the shaft and wheel, allowing the compression of the cushion.

BENHARD YOCH.
